UNITED STATES PATENT OFFICE

156,281

DESIGN FOR A COMBINATION DISHWASHER AND SINK

Ray C. Sandin, Oak Park, Ill., assignor to Hot-point Inc., a corporation of New York

Application August 21, 1948, Serial No. 148,246

Term of patent 14 years

(Cl. D4—2)

To all whom it may concern:

Be it known that I, Ray C. Sandin, a citizen of the United States, residing at Oak Park, in the county of Cook and State of Illinois, have invented a new, original, and ornamental Design for Combination Dishwasher and Sink, of which the following is a specification, reference being had to the accompanying drawing, forming a part thereof.

In the drawing, the single figure is a front perspective view of the combination dishwasher and sink.

I claim:

The ornamental design for a combination dishwasher and sink, as shown.

RAY C. SANDIN.
